UNITED STATES PATENT OFFICE.

FRANK MILTON WINTER, OF WELLINGTON, NEW ZEALAND.

SOUND BOX OF SOUND-REPRODUCING MACHINES.

Application filed August 2, 1924. Serial No. 729,329.

To all whom it may concern:

Be it known that FRANK MILTON WINTER, citizen of the Dominion of New Zealand, residing at Seaside Theatre, Lyall Bay, Wellington, in the Provincial District of Wellington, has invented certain new and useful Improvements in Sound Boxes of Sound-Reproducing Machines, of which the following is a specification.

This invention relates to sound boxes or reproducers, used on gramophones and other machines for the purpose of reproducing the human voice, musical and other sounds.

The object of the invention is to provide improvements whereby such sounds may be reproduced in a better manner than heretofore.

The improvements are directed to that type of sound box or reproducer, wherein is fitted a diaphragm having attached thereto one end of a stylus bar, said improvements consisting firstly in the employment of a metal diaphragm of the nature of aluminium or copper in conjunction with a washer of either vulcanite or mica or material of a similar nature, and secondly the special method of securing the stylus bar to the diaphragm, and thirdly in the means by which the volume of sound can be increased or decreased by varying the depth of the washer or by flexing the diaphragm to decrease or increase respectively the air space between the diaphragm and the back of the sound box or reproducer.

The improvements will be further described in conjunction with the accompanying drawing wherein:

Figure 1 is a vertical sectional view and

Figure 2 a front view of a sound box or reproducer, fitted with the improvements, while

Figure 3 is a detail view illustrating the attachment of the stylus bar to the diaphragm and

Figure 4 is a vertical sectional view illustrating a modification.

In the drawing 1 is the frame of the sound box or reproducer, and has secured thereto by screws 2 the usual back plate 3, the latter containing a central hole 3^a.

A washer 4 of rubber and a tube 5 the inner diameter of each of which is the same as that of the hole 3^a, are secured to the back plate 3 by bolts 6 passing through the latter, the rubber washer 4 and the flange 5^a of the tube 5.

The diaphragm 7 which is metal of the nature of aluminium or copper, preferably the former material, is gripped at its edge between rubber rings 8 held between the back plate 3 and the flange 1^a of the sound box or reproducer.

The stylus bar 9 is mounted on the frame 1 in any known manner preferably by having a screw 10 passed therethrough and entering in the frame, a spring 11 on said screw between the head thereof and the stylus bar 9 keeping the latter pressed against pointed projections 12 from the frame 1.

The upper end of the stylus bar 9 is attached to the diaphragm 7 by a screw 13 of metal or vulcanite, said screw passing through a washer 14 of vulcanite, mica or material of a similar nature and preferably hollow, placed with its hollow side against the back of the diaphragm 7, the central hole 15 in the latter through which the screw 13 passes being of greater diameter than said screw so that the diaphragm does not contact therewith.

In the preferred form the diaphragm 7 is gripped between either the heel or the toe portion only of the upper end 9^a of the stylus bar 9 and the washer 14, although said end 9^a can be made to bridge the hole 15 and cause the diaphragm 7 to be gripped at opposite sides of the hole 15 between the washer 14 and end portion 9^a of the stylus bar 9.

The volume of sound reproduced can be decreased or increased by increasing or decreasing respectively the depth of the washer 14, this method of controlling the volume of sound being adopted where a comparatively thick diaphragm 7 is employed, as shown in Figure 4.

A further method of controlling the volume of sound is to dish the diaphragm 7 so as to decrease or increase the air space 16 between the diaphragm 7 and the back plate 3, decreasing said air space by flexing the diaphragm 7 towards the back plate resulting in a greater volume of sound being reproduced, while dishing or flexing the diaphragm 7 from the back plate 3 results in a decrease in the volume of sound.

When a dished diaphragm 7 is employed, it is preferably flexible enough to permit it to be dished by the application of pressure to the diaphragm or by gripping and pulling the stylus bar 9, while the diaphragm is held in the frame 1.

If desired the volume of sound can be further controlled where the dished diaphragm is used, by varying the depth of the washer 14 as before described.

5 A sound box or reproducer fitted with a metal diaphragm is enabled to stand harder wear and tear than a sound box or reproducer fitted with a mica diaphragm, besides which the volume of sound reproduced is controllable by varying the depth of the washer, or by dishing the diaphragm, or by both means.

10 What I do claim and desire to obtain by Letters Patent of the United States of America is:—

15 1. In a sound box or reproducer of the type specified, the combination with a metal diaphragm, of a stylus bar located on one side of said diaphragm, a hollow non-metallic cup-shaped washer on the opposite side of the diaphragm with the rim of the cup-shaped washer bearing against the diaphragm, and a screw between the cup-shaped washer and the stylus bar securing the parts together.

20 2. In a sound box or reproducer of the type specified, the combination with a metal diaphragm provided with an opening, of a

stylus bar located on one side of said diaphragm, a hollow cup-shaped washer on the opposite side of the diaphragm, and a screw of smaller diameter than the opening in the diaphragm passing through the washer and opening but out of contact therewith, and entering the upper end of the stylus bar for clamping the diaphragm between the washer and the upper end of the stylus bar.

25 3. In a sound box or reproducer of the type specified, the combination with a metal diaphragm provided with an opening, of a stylus bar located on one side of said diaphragm, a non-metallic hollow cup-shaped washer located on the opposite side of the diaphragm with the rim bearing against the diaphragm and surrounding the opening therein, and a screw of smaller diameter than the opening in the diaphragm passing through the washer and opening but out of contact therewith, and entering the upper end of the stylus bar for clamping the diaphragm between the washer and the upper end of the stylus bar.

30 35 40 45 50 In testimony whereof I have signed my name to this specification.

FRANK MILTON WINTER.
